UNITED STATES PATENT OFFICE.

EDWIN LEROY SMITH, OF PHILADELPHIA, PENNSYLVANIA, ASSIGNOR TO OSCAR BRAUCH, OF PHILADELPHIA, PENNSYLVANIA.

LACE-BRAIDING MACHINE.

1,397,299.

Specification of Letters Patent.

Patented Nov. 15, 1921.

Application filed March 20, 1920. Serial No. 367,545.

To all whom it may concern:

Be it known that I, EDWIN LEROY SMITH, a citizen of the United States, residing at Philadelphia, in the county of Philadelphia and State of Pennsylvania, have invented 5 new and useful Improvements in Lace-Braiding Machines, of which the following is a specification.

My invention relates to new and useful 10 improvements in lace braiding machines, and has for its object to provide an exceedingly simple and effective device for imparting an intermittent rotary movement to the driver disks for actuating the bobbin carriers, the 15 movement of said bobbin carriers being controlled by a jacquard or pattern mechanism.

Another object of the invention is to provide means for locking the driver disks after 20 they have made the desired rotation, said locking motion taking place simultaneously with the disengagement of the operating rack from the driver disks.

With these ends in view, this invention 25 consists in the details of construction and combination of elements hereinafter set forth and then specifically designated by the claims.

In order that those skilled in the art to 30 which this invention appertains, may understand how to make and use the same, I will describe its construction in detail, referring by numerals to the accompanying drawings forming a part of this application, in which:

35 Figure 1, is a fragmentary plan view of the raceway plate of a lace making machine illustrating the application of my invention, several of the intersecting race circle openings being shown with the driver disks there- 40 in, a portion of said plate being broken away to illustrate the location of the operating rack.

Fig. 2, is an elevation thereof having portions broken away.

45 Fig. 3, is a section at the line 3—3 of Fig. 1.

Fig. 4, is a plan view of one of the locking disks, and

50 Fig. 5, is an edge view thereof showing the manner in which the locking dog engages said disk.

In carrying out my invention as here embodied, 2 and 3 represent the bottom and top plates respectively arranged as usual in 55 machines of this character the top plate hav-

ing intersecting race circle openings 4 while in the bottom plate 2 are mounted the bearings 7 in which are journaled the posts 5 arranged centrally of the race openings upon which are mounted the carrier driver disks 6 in the race circle openings 4.

On each of the posts 5 is slidably mounted a drive or operating clutch 8 adapted to be engaged by a clutch arm 9 adjustably secured to each of the rods 10, the latter slidably mounted in the bottom and top plates 2 and 3 and normally forced upward by a spring 11 coiled about said rods and engaging the clutch arm 9 as the movable member and the lower plate 2 as the stationary member and the lower end of each rod 10 has a foot 12 to which is fastened the jacquard operated lever 13 as shown.

The driving clutch 8 is also provided with two upright pins 14 which slidably pass 75 through suitable holes 15 in the driver disks 6 while from the opposite face of the operating clutch depend the downwardly projecting gear pins 16 which are intermittently moved into the path of travel of the rack 17 80 which is journaled in suitable brackets 18 and which is driven in any suitable or approved manner.

On the lower end of each post 5 is mounted a locking disk 19 having a squared central 85 opening 20 registering with the squared end of the post 5 and held in place by a nut 21 or its equivalent. At two diametrically opposite points on the circumference of each disk 19 are formed notches 21 which are produced by partially cutting the metal from said disk and opening the same upward at converging angles so as to form centering walls 22 adapted to be engaged by the wedge shaped nose 23 of the locking dog 24 adjustably mounted upon the rod 10 so as to move therewith in unison with the clutch arm 9 and when said nose is in engagement with one of the notches 21 the driver disk on the post carrying such locking disk will be centered and securely locked in the desired position.

The several driver disks 6 with their coacting carrier rest recesses 25 and carrier engaging arms 26 operate the bobbin carriers 105 27 in the usual well known manner for lace making, said bobbin carriers each comprising a spindle 28 and two opposed disks 29 and 30, one of which rests on each side of the top plate 3.

From the foregoing description it will be seen that when the rod 10 is actuated by the jacquard or pattern machine the locking dog 24 will be drawn out of engagement with the locking disk 19 simultaneously with the moving downward of the operating clutch 8 through the medium of the clutch arm 9. When the operating clutch is drawn downward the gear pins 16 will register with the rack 17 and the oscillating movement thereof will rotate the operating clutch member 8 and likewise the carrier disk 4 through the medium of the upwardly projecting pins 14 thereby causing the bobbin carrier or carriers which are in engagement with the operated disk to be carried to the opposite side of the race circle and as soon as the movement has been completed and the rod 10 released by the jacquard mechanism the spring 11 will immediately force said rod upward to disengage the gear pins 16 from the rack and simultaneously cause the locking disk 19 and if the rotation of the carrier disk was not sufficient to move the bobbin carrier to the exactly desired position then when the tapered or wedge shaped nose 23 registers with one of the notches 21 and engages the inclined walls 22 the locking disk will be centered which will obviously move the bobbin carrier to its proper position.

Of course I do not wish to be limited to the exact details of construction as herein shown as these may be varied within the limits of the appended claims without departing from the spirit of my invention.

Having thus fully described my invention, what I claim as new and useful is:

1. A lace braiding machine comprising a raceway plate having intersecting race circle openings, a bottom plate, bearings mounted in said bottom plate, centrally of the race circle openings, posts journaled in said bearings, a driver disk carried by each of said posts and located in the race circle openings, an operating clutch member slidably mounted on each of said posts, upwardly projecting pins carried thereby and slidably mounted in the coacting driver disk, gear pins depending from said operating clutch member, an oscillating rack adapted to be engaged by said gear pins whereby a rotary motion may be transmitted to the driver disk, and means for sliding the operating clutch member on its post to move the gear pins into the path of travel of the rack.

2. A lace braiding machine comprising a raceway plate having intersecting race circle openings, a bottom plate, bearings mounted in said bottom plate, centrally of the race circle openings, posts journaled in said bearings, a driver disk carried by each of said posts and located in the race circle openings, an operating clutch member slidably mounted on each of said posts, upwardly

projecting pins carried thereby and slidably mounted in the coacting driver disk, gear pins depending from said operating clutch member, an oscillating rack adapted to be engaged by said gear pins whereby a rotary motion may be transmitted to the driver disk, a rod slidably mounted in the plates adjacent each post, a clutch arm adjustably mounted on said rod and engaging the operating clutch member for actuating the latter when the rod is moved by the jacquard or pattern machine, and means for normally forcing said rod in that direction which will force the operating clutch member upward or out of engagement with the rack.

3. A lace braiding machine comprising a raceway plate having intersecting race circle openings, a bottom plate, bearings mounted in said bottom plate, centrally of the race circle openings, posts journaled in said bearings, a driver disk carried by each of said posts and located in the race circle openings, an operating clutch member slidably mounted on each of said posts, upwardly projecting pins carried thereby and slidably mounted in the coacting driver disk, gear pins depending from said operating clutch member, an oscillating rack adapted to be engaged by said gear pins whereby a rotary motion may be transmitted to the driver disk, a rod slidably mounted in the plates adjacent each post, a clutch arm adjustably mounted on said rod and engaging the operating clutch member for actuating the latter when the rod is moved by the jacquard or pattern machine, means for normally forcing said rod in that direction which will force the operating clutch member upward or out of engagement with the rack, a locking disk secured to each post, said locking disk having diametrically opposite notches in its outer circumference with converging centering walls and a locking dog adjustably mounted on each rod having a wedge shaped nose for registration with the notches in the locking disk, said dog being operable simultaneously with the operating clutch member.

4. In a lace braiding machine, a raceway plate, a bottom plate, posts carried by the bottom plate and projecting through the raceway plate, driver disks on said posts, an operating clutch member mounted on each of said posts, upwardly projecting pins carried by said clutch members for coaction with the driver disks, gear pins depending from the operating clutch members, an oscillating rack adapted to be engaged by said gear pins whereby a rotary motion may be transmitted to the driver disks, and means to actuate the operating clutch members to move the gear pins into engagement with the rack.

In testimony whereof I have hereunto affixed my signature.

EDWIN LEROY SMITH,
